GAME APPARATUS

Charles C. Carter, Cedar Rapids, Iowa

Application May 17, 1939, Serial No. 274,194

2 Claims. (Cl. 273—85)

My invention relates to that class of so-called parlor game apparatus in which the contending players use paddles on paddle rods for propelling a light weight ball such as a ping-pong ball toward 5 and into a goal at the end of the playing field.

The object of my invention is to provide a game apparatus of this class by means of which the players may develop and utilize a high degree of skill in impelling the ball longitudinally of the 10 playing field by a swinging movement of the paddles, transversely by a sliding movement of the paddles, and diagonally of the field by striking the ball with the beveled sides of the blades, and a twisting motion or "English" may be applied to the ball by striking the ball with a beveled surface of the paddle by a twisting motion 15 of the paddle.

Referring to the accompanying drawings:

Figure 1 shows a perspective view of my improved game apparatus;

Figure 2 shows an enlarged detail top view with a portion of one of the paddle rods of a paddle secured thereto;

Figure 3 shows an enlarged detail view of a 25 portion of one of the paddle rods of a paddle secured thereto, and showing the front or ball-striking face of the paddle;

Figure 4 shows an edge view of same, the position of the paddle being shown by dotted lines in 30 various positions of its adjustment;

Figure 5 shows an enlarged detail view, partly in section, illustrating a modified form of the player-protecting heads mounted on the paddle rods;

Figure 6 shows a top view of my improved 35 game apparatus, the position of some of the paddle rods being shown by dotted lines in position where they will be moved by the players. The arrows in said figure indicate the various angles 40 at which the ball can be driven by the paddles; during the various movements of the paddles;

Figure 7 shows a central longitudinal sectional view of the playing field and upright members with the upright side member shown in an elevated position;

Figure 8 shows a vertical longitudinal view of my improved game apparatus;

Figure 9 shows an enlarged detail view illustrating a modified form in which the paddles are 50 yieldingly supported upon the paddle rods; and

Figure 10 shows a view similar to Figure 2 illustrating a modified form of the striking face of the paddle.

My improved game apparatus comprises a playing field member 10 which is preferably smooth

and flat. At the ends thereof there are the upright end members 11, each of which has a goal opening 12, and a pocket 13 for the ball, which is indicated by the reference numeral 14.

As illustrated in Figure 7, the upright side 5 members 15 are formed with rounded notches at 16, equally spaced apart, and a bar 17 is detachably mounted above the side member 15 by means of the screws 18, and this bar has rounded 10 notches 19.

Mounted in the notches 16 and 19 are the paddle rods 20. These are smooth and round and have free longitudinal sliding movements in the side walls, and are also capable of freely rotating. One end of each rod is termed the handle end, 15 and on the other there is a player-protecting head. This, as shown in Figure 4, comprises a rounded metal disc 21 held to the end of the rod by a screw 22, and it is in diameter much larger than the rod and serves the purpose of preventing 20 injury to players when the rod is pushed rapidly in a direction away from the side wall of the game device.

On each of the paddle rods there are two paddles, spaced apart from each other and so positioned on the rod that they will engage one or the other of the side walls 15 when the rod is moved to its limit in either direction. The body of the paddle is indicated by the reference numeral 23. This is formed with a notch at one side to receive 30 a paddle rod, as shown in Figure 4, and it is held to the paddle rod by the screw 24. Each paddle has a vertical, centrally-arranged striking face illustrated in Figure 3 by the reference numeral 25, and on opposite sides are the inclined striking faces 26 which extend outwardly and rearwardly relative to the face 25.

In the modified form shown in Figure 10 I have 35 shown another striking face 27 in the form of an arc.

In the modified form shown in Figure 9 the paddle is held to the rod by a bolt 28, and this bolt is arranged to permit a slight rotary movement of the paddle relative to the rod. An extensible coil spring 29 is applied to the bolt and 45 bears against the adjacent surface of the paddle for yieldingly holding the paddle relative to the paddle rod.

In practice, and when it is desired to assemble 50 the game apparatus, the bars 17 are first removed and the paddle rods with their paddles fixed thereon are mounted in the notches 16, and the bars 17 are then screwed to the upright side walls. This makes it easy for an operator to remove the paddle rods and place them upon 55

the playing field within the uprights for shipping and storing.

The arrangement of the paddles upon the paddle rods is shown in Figure 6. The paddle rod at the right has the paddles on the side away from the adjacent goal as the operator of this paddle rod is always striving to drive the ball away from his goal. Each alternate paddle rod has the paddles arranged in the same 10 way and preferably the alternate paddle rods are made of different colors so that the players may not become confused as to which paddle rods belong to him.

The game may be played by two or more persons, and the ball which is used is very light and resilient and is of the kind commonly known as ping-pong balls. To commence play, the ball is dropped in the center of the playing field and then the players move the paddle rods both with 20 a sliding longitudinal movement and with a rotary movement for driving the ball toward an opponent's goal. I have found in practice that a player soon learns to utilize the paddles for applying a number of different kinds of movement to the ball. For instance, when the ball is close to the striking face of the paddle, the operator simply imparts a rotary motion to the paddle rod and drives the ball straight forwardly longitudinally of the field, as indicated by 25 the arrow 30 in Figure 6. In some instances it is desirable to drive the ball diagonally toward one of the side walls, and this is done by moving the paddle rod longitudinally and causing the in-

clined side striking face to engage the ball, as shown by the arrow 31 in Figure 6. Furthermore, I have found in practice that the player, by skilful manipulation of the paddle may, by means of a combined lengthwise rotary and sliding 5 movement of the paddle, cause the inclined side edge of a paddle to strike a ball and give it a twisting motion corresponding to the so-called "English" which is imparted to balls in billiard games.

The object of the game is to place the ball in the opponent's goal pocket.

I claim as my invention:

1. In a game apparatus, a playing field, upright side members at the sides thereof, a series 15 of paddle rods slidably and rotatably mounted in the side members, and paddles carried by the rods, each paddle being formed with a notch at its rear upper portion to receive the paddle rod, a bolt extended through the rod and paddle and 20 permitting a limited rotary movement of the paddle relative to the rod, and a spring carried by the bolt and pressing against the paddle for yieldingly holding the paddle toward the rod.

2. In a game apparatus, a playing field having 25 upright sides, a series of paddle rods rotatably and longitudinally slidably mounted in said upright sides, paddles carried by the paddle rods and having a flat striking face parallel with the paddle rod and flat striking faces at the sides 30 thereof, inclined outwardly and rearwardly from the first mentioned striking face.

CHARLES C. CARTER.
